UNITED STATES PATENT OFFICE.

BURCHARD THOENS, OF NEW ORLEANS, LOUISIANA.

ABSORPTION ICE AND REFRIGERATING MACHINE.

SPECIFICATION forming part of Letters Patent No. 669,934, dated March 12, 1901.

Application filed June 11, 1900. Serial No. 19,920. (No model.)

To all whom it may concern:

Be it known that I, BURCHARD THOENS, a subject of the Emperor of Germany, residing at New Orleans, in the parish of Orleans and State of Louisiana, have invented certain new and useful Improvements in Absorption Ice and Refrigerating Machines; and I do hereby declare the following to be a full, clear, and exact description of the invention, such as will enable others skilled in the art to which it appertains to make and use the same.

My invention relates to improvements in ice and refrigerating machines of the absorption type; and the object of the invention is to provide an apparatus by which may be accomplished a fuller and a more nearly perfect exchange of the differences of temperature between the different fluids used and to obtain a greater proportion of condensed or distilled water for freezing purposes than has been heretofore obtained with a given amount of fuel required for the operation of the machine.

Generally stated, my improvements consist in means for passing the different hot fluids in separate coils submerged in water in a closed vessel, and thereby converting the water into steam, which steam is afterward conducted to a second vessel and there condensed on the surfaces of coils through which the cold fluids pass. In the first vessel the hot fluids are partially cooled and in the second vessel the cold fluids are partially heated.

All parts of the apparatus are arranged with a view to deriving the greatest benefit for the purposes mentioned, as will hereinafter be more fully described.

My invention will be understood by reference to the accompanying drawing, wherein are shown such parts of an absorption ice or refrigerating machine as are essential for a clear understanding of the invention, parts referred to as "ammonia-condenser," "ammonia-pump," "absorber," "weak-liquor cooler," "water-cooler," "boiler-pump," "vacuum-pump," &c., being understood to refer to devices of any approved construction or type suitable for the purposes required, and being well known in the art are not illustrated. The drawing illustrates a vertical sectional view of such portions of the apparatus as embody my invention and are neces-

sary to a complete understanding thereof and its mode of operation.

The parts of the machine illustrated in the drawing are designed especially for ice-making, although they may be used for other refrigerating purposes.

A represents a generator containing a steam heating-coil *a*, which enters the bottom of the generator, and a rich-liquor-heating coil *b*, which enters near the upper portion of the generator and the lower end of which terminates in a stand-pipe *c*, provided at its upper end with a spray-plate *d*. The general form of this generator, the coil *b*, stand-pipe *c*, and spray-plate *d* I do not claim as new in connection with this apparatus, as a patent has been granted to me for these features, No. 284,515, dated September 4, 1883, and I have introduced these here in combination with the new features hereinafter described for the sake of better illustration.

A closed vessel *B* contains a coil *e* for hot ammonia-gas, one end of which coil is connected with the upper part of the generator *A*, and the other end of which is connected with an ammonia-gas condenser. (Not shown.) The vessel *B* contains also a coil *f* for weak liquor. The pipe leading to said coil *f* starts from the lower part of the generator *A*, and after passing through the vessel *B* passes to a weak-liquor cooler. (Not shown.) A third coil *g* in the vessel *B* is provided for the passage of any available exhaust-steam from pumps or other source. One end of the pipe leading to the coil *g* enters a suitable separator *F* and connects with an exhaust-steam receiver *E*, whence it passes through another separator *F*, and after passing through the vessel *B* terminates in the lower part of the second closed vessel *C*. The upper part of the vessel *C* has free connection, by means of a pipe *h*, with the upper part of the vessel *B*. The vessel *C* contains a coil *i* for cold rich liquor, which is forced through such coil by means of an ammonia-pump from the absorber, (not shown,) and the outlet of the said coil is connected with the top end of the rich-liquor-heating coil *b*, located within the generator *A*. The vessel *C* also contains a coil *j*, the upper end of which coil is connected with a cooling-water supply, and the outlet of which connects with a filter *D* (illus-

trated in diagram) of any suitable type. The outlet *k* of filter *D* is connected with the lower portion of the vessel *B* and by a branch pipe *k'* is connected with the boiler-feed pump, (not shown,) which supplies the boiler of the plant. The pipe *K* is preferably provided with a valve at *n* adjacent to the vessel *B*. The vessel *C* contains a third coil *l*, connected at one end with a cooling-water supply, the pipe at the other end of the coil being allowed to carry off water from the said coil as waste.

The outlet of the steam heating-coil *a* in generator *A* enters the lower part of vessel *C*. A pipe *m* connects the vessel *C* with a water-cooler (not shown) for conveying from the said vessel *C* condensed or distilled water for use for freezing purposes. A pipe *g* connects the vessel *C* with a vacuum-pump. (Not shown.)

The operation of the machine is as follows: A solution of ammonia-gas in water, which enters the generator *A* through the pipe *i* and passes through the coil *b*, discharges into the stand-pipe *c* in the lower portion of the generator and is heated in the generator *A* by the surrounding gas and by contact with the steam-coil *a*. The gas is thereby separated from the water and passes off through the pipe *e*, the hot weak liquor remaining in the generator. The condensed water formed in the coil *a* passes through the pipe *a* out of the bottom of the generator into the vessel *C*. The hot weak liquor passes from the generator *A* through the pipe *f* and its coil within the vessel *B*, through the latter vessel, which is partially filled with water, and in the said vessel the hot weak liquor passing through the coil *f* parts with some of its heat by evaporating some of the surrounding water within the said vessel, and it thence passes out to a weak-liquor cooler (hereinbefore referred to, but not shown) to be further cooled. The hot ammonia-gas escaping from the generator through the pipe *e* passes through the coil in such pipe in the vessel *B* and thence on to the ammonia-condenser (not shown) to be liquefied. During its passage through the coil *e* in the vessel *B* this hot ammonia-gas parts with some of its heat by evaporating some of the water surrounding such coil, and thereby becomes partially cooled. All exhaust-steam passes, by way of the pipe *g*, through the separator *F* into the exhaust-steam receiver *E* and thence through another separator *F* and through the coil in the vessel *B* into the vessel *C*. During its passage through the coil *g* in the vessel *B* the exhaust-steam is condensed by evaporating some of the water surrounding such coil within the vessel *B*, and this condensed water is discharged into the vessel *C*. Through the pipe *h*, which connects the upper parts of the vessels *B* and *C*, all the steam generated in the vessel *B* by heat from the coils *e*, *f*, and *g* is conducted into the vessel *C*. (Any grease extracted by the sep-

rators *F* and *F* from the exhaust-steam passes by connections *o o* into the lower part of the exhaust-steam receiver *E*, from where it is discharged by means of a waste-pipe *p*, so that no portion of such grease as may be contained in the exhaust-steam will enter the vessel *C*.) Cold strong liquor is forced, by means of an ammonia-pump, (not shown,) from the absorber through the pipe *i* and its coil within the vessel *C* on to the generator *A*, where the pipe *i* connects with the coil *b* in the upper part of the generator. In this manner the cold strong liquor is delivered hot into the generator for the separation of the ammonia-gas therefrom, as hereinbefore described. As stated, the strong liquor enters the vessel *C* through the coil in the pipe *i* in a cold state, and the pipe *j* conducts cold water from a suitable source through this coil within the vessel *C* to the filter *D*. The steam generated in the vessel *B* passing over into the vessel *C* is condensed on the cold surfaces of the rich-liquor coil *i*, the cooling-water coil *j*, and the coil *l*, through which a stream of cooling-water also passes. The condensation of this steam in the vessel *C* causes the partial heating of the rich liquor passing through the coil *i* and of the water passing through the coil *j*. Thus the rich liquor passes from the coil in the vessel *C* to the coil *b* in the generator *A* in a partially-heated condition, thus lessening the amount of heat necessary to cause its separation in the generator, and the water passing through the coil *j* in the vessel *C* is delivered to the vessel *B* in a partially-heated state, thus facilitating its evaporation within the vessel *B*. A portion of the water is delivered directly through the pipe *K* to the vessel *B* after passing through the filter, the amount being regulated by the valve *n*, and the balance of the water is conducted by the branch pipe *K'* to the boiler-pump (not shown) which supplies the boiler used for operating the ice plant. It is also apparent that the water thus fed to the pump is partially heated and the production of steam in the boiler correspondingly assisted.

The third coil *l*, which passes through the vessel *C*, is provided for the passage of additional cooling-water to insure a perfect and complete condensation of all steam entering the said vessel, and this water is allowed to run off as waste water through the pipe *l*, as shown. Should more condensed water be needed for freezing purposes, additional steam may be introduced by a branch pipe *r*, (indicated in dotted lines,) connected with the pipe *g*. All of the condensed water collected in the vessel *C* is conducted by means of the pipe *m* to the distilled-water cooler (not shown) to be further cooled for freezing purposes.

The vessel *C* has connected thereto a pipe *q*, to which would be attached a vacuum-pump, (not shown,) so as to provide means for lowering the boiling-point of the water surrounding the coils *e f g*, and this also provides means for withdrawing from the con-

densed or distilled water accumulating in the vessel C any air or gases that may be contained in the water.

In order to be able to discharge the water from the vessel C, the latter must be elevated to a position corresponding to the extent of the vacuum produced therein; the pipe *m* serving after the manner of a water-barometer.

In the arrangement hereinbefore described, and shown in the accompanying drawing, it will be seen that the vessels B and C embody in themselves alone the various elements—namely, an exchanger, a rich-liquor heater, a steam-condenser, a reboiler, and a feed-water heater—each of which elements is necessary to the operation of an absorption ice-making machine, and most of which, if not all, ordinarily constitute separate elements of an ice-making plant.

From the foregoing description it will be seen that I accomplish the following notable results—namely, by passing hot ammonia-gas, hot weak liquor, and exhaust-steam through coils in a closed vessel containing the water I evaporate the water surrounding these coils and thereby cooling the fluids passing through these coils to or near to the temperature of the water, and thus save cooling-water necessary for further cooling in the ammonia-gas condenser and weak-liquor cooler, and, further, by passing the steam generated thereby over into another closed vessel, wherein it is condensed, I obtain not only the condensed water from the actual exhaust-steam, condensed in the coil leading from pumps and from the heating-coil in the generator, but I obtain an additional amount of condensed water due to the evaporation of the water in the first-named vessel by contact-coils, coils through which such hot fluids pass. In addition to this I obtain hot feed-water for the boiler.

Having thus described my invention, what I claim, and desire to secure by Letters Patent of the United States, is—

1. In an absorption ice or refrigeration machine, the combination with a closed vessel; a second closed vessel, and a steam connection between said vessels; of a plurality of coils located in the first vessel; a gas-generator; a strong-liquor connection between one of the coils in the second vessel and the said generator; a weak-liquor connection between said generator and one of the coils in the first vessel; a cold-strong-liquor connection with one of the coils in the second vessel; cold-water connections with other of the said coils in said second vessel; connections between a cold-water coil of the second vessel and the interior of the first vessel; the first vessel receiving partially-heated water from a coil in the second vessel and the second vessel receiving steam from the vaporization of the water in the first vessel, substantially as described.

2. In an absorption ice or refrigeration ma-

chine, the combination with a closed vessel, a second closed vessel, and a steam connection between the said vessels; of a plurality of coils located in the first vessel; a gas-generator; a strong-liquor connection between the generator and one of the coils of the second vessel; a weak-liquor connection between the said generator and one of the coils of the first vessel, a heated-gas connection between 70 the generator and another of the coils in the first vessel; a cold-strong-liquor connection with one of the coils in the second vessel; cold-water connection with other of said coils in said second vessel; connections between a 75 cold-water coil in the second vessel and the interior of the first vessel; the first vessel receiving partially-heated water from a coil in the second vessel, and the second vessel receiving steam from the vaporization of the 80 water in the first vessel, substantially as described.

3. In an absorption ice or refrigeration machine, the combination with a closed vessel, a second closed vessel, and a steam connection between the said vessels; of a plurality of coils located in the first vessel; a gas-generator; a strong-liquor connection between the generator and one of the coils of the second vessel; a weak-liquor connection between 90 the said generator and one of the coils of the first vessel; a cold-strong-liquor connection with one of the coils in the second vessel; cold-water connection with other of said coils in said second vessel; connections between a cold-water coil in the second vessel and the interior of the first vessel; a steam connection between one of the coils of the first vessel and the interior of the second vessel, the steam thus entering being condensed in the 95 second vessel; the first vessel receiving partially-heated water from a coil in the second vessel, and the second vessel receiving steam generated from the water in the first vessel, substantially as described.

4. In an absorption ice or refrigeration machine, the combination with a closed vessel, a second closed vessel and a steam connection between the upper portions of said vessels; of a plurality of coils located in the first vessel; a gas-generator; a strong-liquor connection between one of the coils in the second vessel and said generator; a weak-liquor connection between the said generator and one of the coils in the first vessel; a heated-gas connection between the generator and another of the coils in the first vessel; a cold-strong-liquor connection with one of the coils in the second vessel; cold-water connections with others of the said coils in said second vessel; connections between one of the cold-water coils in the second vessel and the interior of the first vessel; a steam connection between one of the coils in the first vessel and the interior of the second vessel; the first vessel receiving partially-heated water from a coil in the second vessel and the second vessel

sel receiving steam from the vaporization of the water in the first vessel, substantially as described.

5. In an absorption ice or refrigeration machine, means for exchanging the temperatures of the different fluids used, consisting of a group of hot-fluid coils submerged in water; a group of cold-fluid coils; hot gas, and hot-weak-liquor connections with the coils of the 10 hot-fluid group; cold-strong-liquor and cold-water connection with the coils of the cold-fluid group; and means for conducting the steam from the water vaporized by contact with the hot-fluid coils into contact with the cold-fluid coils, substantially as described.

15. In an absorption ice or refrigeration machine, means for exchanging the temperatures of the different fluids used, consisting of a group of hot-fluid coils submerged in water; a group of cold-fluid coils; hot gas, and hot-weak-liquor connections with the coils of the hot-fluid group; cold-strong-liquor and cold-water connection with the coils of the cold-fluid group; a connection between a water-coil of the cold-fluid group and the space surrounding the group of hot-fluid coils; and a

30 pipe conducting the steam generated from the water in contact with the hot-fluid coils over into contact with the cold-fluid coils, substantially as described.

35 7. In an absorption ice or refrigeration machine, means for exchanging the temperature of the different fluids used, consisting of a group of hot-fluid coils submerged in water; a group of cold-fluid coils; hot gas, and hot-weak-liquor connections with the coils of the hot-fluid group; cold-strong-liquor and cold-water connection with the coils of the cold-fluid group and the space surrounding the group of hot-fluid coils; and a pipe conducting 40 the steam generated from the water in contact with the hot-fluid coils over into contact with the cold-fluid coils; and a pipe leading from the strong-liquor coil in the cold-fluid group to a gas-generator, substantially as described.

45 In testimony whereof I affix my signature in presence of two witnesses.

BURCHARD THOENS.
